(57) **CLAIM**

The ornamental design for a front panel for radiators, as shown and described.

DESCRIPTION

FIG. 1 is a perspective view of a first embodiment of a front panel for radiators showing the invention;

FIG. 2 is a front elevation view thereof;

FIG. 3 is a top plan view thereof;

FIG. 4 is a left side elevation view thereof;

FIG. 5 is a rear elevation view thereof;

FIG. 6 is a bottom plan view thereof;

FIG. 7 is a right side elevation view thereof;

FIG. 8 is a perspective view of a second embodiment of a front panel for radiators showing the invention;

FIG. 9 is a front elevation view thereof;

FIG. 10 is a top plan view thereof;

FIG. 11 is a left side elevation view thereof;

FIG. 12 is a rear elevation view thereof;

FIG. 13 is a right side elevation view thereof; and,

FIG. 14 is a bottom plan view thereof.
